UNITED STATES PATENT OFFICE

ISAAC A. BAUM, OF CHICAGO, ILLINOIS

METAL JAMB FOR UNPLASTERED WALLS

Application filed April 14, 1930. Serial No. 444,247.

My invention relates to building construction and more particularly to a metal jamb for use with unplastered tile walls.

In building construction, it has been found difficult to provide a good, rigid construction for a door jamb for use in association with unplastered tile. Frequently the association of wooden jambs has proven very unsatisfactory due to the warping and shifting thereof, and the lack of inherent strength and rigidity.

However, an object of my invention is to provide a metal jamb construction that is rigid, simply and readily installed by unskilled labor, and economically manufactured.

A further object of my invention is to provide suitable metal jamb construction adapted for use with unplastered tile or masonry walls.

A further object is to provide a suitable jamb for association with a double hollow tile wall, having a space between the opposite tiles or for use in a single course tile or masonry wall. This is accomplished by securing a continuous anchor strip to the web of the jamb which is adapted to project into the opening at the edge of the wall. Thereafter, concrete, mortar or other filler is placed in the opening, thus surrounding the anchor strip and securely holding it against movement.

A further object of my invention is to provide efficient anchoring means for jambs, thus preventing any separation thereof from the wall when the same is installed and the wall constructed.

The invention will be more readily understood by reference to the accompanying drawings, in which

Fig. 1 is a plan view showing a metal jamb installed in accordance with my invention;

Fig. 2 is a vertical sectional view across a wall with the jamb installed the section being on the line 2-2 of Fig. 1;

Fig. 3 is a perspective view of one form of tile anchor;

Fig. 4 is a fragmental perspective view of a modified form of jamb;

Fig. 5 is a fragmental perspective view of another form of a modified jamb;

Fig. 6 is a plan view of a jamb constructed in a solid wall;

Fig. 7 is a plan view of a modified form of jamb construction; and

Fig. 8 is a vertical sectional elevation of the jamb shown in Fig. 6 on the line 8-8 of Figure 6.

By referring to the drawings, Figs. 1, 2 and 3, it will be seen that the preferred form of my invention comprises a metal frame member comprising the web 10 and flanges 11, the margins of which are rebent to form anchors, the angularly bent strips 12, 13 constituting an anchor having one margin 15, 16 thereof secured to the inside of the web 10. Preferably, the strip 12 is bent at its internal margin to provide contact with a face of the other strip 13. The strips 12, 13 are provided with elongated apertures 17 at various spaced intervals in the length thereof through which are passed the ties 18 lying within the masonry joints and adapted to prevent the separation of the un-plastered tile 19, 20 when the concrete or other plastic material 21 is poured into the space therebetween. If desired, the reinforcing bars 22 may also be inserted between the walls. The strip 13 may have additional apertures 23 at the outer margin through which the binding material may flow.

In installation the tile are progressively built up from the floor, the jamb being temporarily set up closing the outside edges of the opposite tile, as illustrated. As the wall is built up the ties 18 are passed through the apertures 17 to join the opposite tile, and this operation may continue at the setting of each tier of tile if desired. When the walls are built up a sufficient height, concrete, or mortar 21 is poured, thus filling the space between the walls and tending to separate the tile. This is prevented by the embedded ties 18. The concrete may be found to be embedded also in the space between the strips 12, 13 thus locking them against movement when the concrete hardens. The concrete is also found to encompass the anchors 11 formed on the flanges of the jamb.

It will thus be seen that upon the harden-

ing of the concrete, the jamb of my invention is as firmly and rigidly bound as though it were a part of the wall itself. In addition, the parts are all anchored, including the tiles, 5 thus preventing any subsequent separation thereof.

In Figs. 4 and 5, I have illustrated another form of jamb construction, for use in a similar wall construction.

10 In the form shown in Fig. 4 the jamb comprises a channel shaped metal member 24, the flanges of which contact the inner faces of the tile in the wall opening. The Z-shaped strip having the projection 26 provides the 15 jamb facing.

In the form shown, in Fig. 5 the jamb comprises the two-sided bent strip 27 providing a web and a flange, and the angle strip 28 providing an additional web and flange. The 20 strip 28 likewise has a projection 29 for a jamb facing. The flanges of the strips 27 and 28 are adapted to contact the inner tile faces. In the constructions shown in Figs. 4 and 5, the ties 18 may also be employed to prevent 25 the separation of the opposite tiles by inserting the same through the apertures 30, 31.

In Figs. 6, 7, and 8 I have shown a modified form of the jamb construction herein contemplated. The two forms illustrated are 30 identical with the exception of the location of the door stop.

The modified form shown in Figs. 6 and 7 is adapted for use with a single course tile or masonry wall in which the tile adjacent the 35 wall opening are provided with a vertically extending opening on the outside edges. The construction contemplated is shown in Figs. 6 and 7 in which I illustrate the superposed tile or masonry elements 32 having the registering openings 33 at the edge thereof. The jamb comprises the web 34 and bent flanges 35 which contact the edge of the wall. The anchoring means comprises an angularly 40 bent strip having the faces 36, 37 and secured to the inner face of the web at 38, 39. The 45 margins of the anchors are provided with the apertures 40, 41 for the reception of the wire anchor 42 adapted to lie between the masonry joints. The anchor comprising the strips 36, 50 37 is provided with elongated apertures 43 through which may be inserted the flat tie 44 shown in dotted lines in Fig. 6 lying in the masonry joints.

When the frame member is set up and the 55 anchors properly secured, the opening 33 may be then filled with mortar or the like which surrounds the strip anchor within the opening and firmly secures the same.

It is evident that the jamb constructions 60 herein disclosed may be simply manufactured, fabricated at the shop and delivered ready to set up. Thus, unskilled labor may be freely used in installing jambs.

Obviously modifications may be made in 65 the construction herein disclosed and I do not

wish to be limited except as indicated in the appended claims.

I claim:

1. In a device of the class described, the combination of oppositely disposed tiles forming a wall, means for preventing the lateral separation of said tiles, and a channel shaped metal jamb, a portion of said jamb being disposed within said wall. 70

2. In a device of the class described, the combination of oppositely disposed, superposed tile having a predetermined spaced relation therebetween forming a wall, a channel shaped metal jamb member, the flanges of which are bent and contact the said tiles, metal strips secured to the web of said jamb and projecting between said tiles adapted for use as anchors and means projecting through said strips at the tile joints to prevent the lateral separation of said tiles. 75

80 3. In a device of the class described, the combination of a tile wall, comprising a plurality of oppositely disposed, superposed tiles having a predetermined spaced relation, a channel shaped metal jamb, the flanges of which are rebent and have contact with the edges of said superposed tile, a pair of parallel strips secured to the inner face of the web and projecting within said wall to serve as an anchor, and a tie passing through apertures 90 in said strips at the tile joints adapted to join said tile and prevent lateral separation of the same. 95

100 4. A wall having an opening, said wall being composed of masonry elements located in laterally spaced apart relation, the edges of the masonry elements at the wall opening being finished for a desired decorative appearance, a metal jamb of a width at least equal to the spacing separating said masonry elements, an anchor projecting rearwardly from the jamb into said space, means tying together the respective masonry elements, and plastic material filling said space and surrounding said anchor and said tying 105 means. 110

115 5. Metal jamb construction, comprising in combination a built up masonry wall having a continuous vertical opening therein adjacent the wall opening, a bent metal jamb adapted to enclose the open edge of said wall, a continuous strip secured to the web of said jamb and projecting into said wall opening for use as an anchor, means received within said masonry joints and passing through said strip adapted for use as an anchor, and plastic material filling said wall opening and surrounding said strip. 120

125 6. Metal jamb construction comprising in combination a built up masonry wall having a continuous vertical opening therein adjacent the wall opening, a bent metal jamb adapted to enclose the open edge of said wall, a continuous anchor secured to the web of said jamb and projecting into said wall open- 130

ing, means received within said masonry joints and passing through said continuous anchor providing a tie, and plastic material filling said wall opening and surrounding said anchor.

5 7. Metal jamb construction comprising in combination a built up masonry wall having a continuous vertical opening therein adjacent the wall opening, a bent metal jamb
10 adapted to enclose the open edge of said wall, a continuous anchor secured to the web of said jamb and projecting into said wall opening, means received within said masonry joints and passing through said continuous
15 anchor providing a tie, wire means secured to said jamb and lying within said masonry joints to provide another anchor, and plastic material filling said wall opening and surrounding said anchor.

20 In testimony whereof I have affixed my signature.

ISAAC A. BAUM.
